UNITED STATES PATENT OFFICE.

RENÉ BRETON, OF PARIS, FRANCE.

EXPLOSION-MOTOR.

982,468.

Specification of Letters Patent. Patented Jan. 24, 1911.

Application filed February 25, 1910. Serial No. 545,964.

To all whom it may concern:

Be it known that I, RENÉ BRETON, citizen of the Republic of France, residing in Paris, France, have invented new and useful Improvements in Explosion-Motors, which invention is fully set forth in the following specification.

This invention relates to an extra-light motor of the kind in which the cylinders, together with their pistons and connecting rods and the casing, rotate about a fixed shaft or axle, the motion being transmitted from the casing itself.

The motor of the present invention comprises two coinciding sets of six cylinders, each set consisting of three groups of two cylinders set V-wise and so that the angles of the V's are reentering angles, or, in other words, so that the set forms a regular hexagon having reentering angles. By this means great symmetry of the rotating system relatively to the center of rotation is obtained, and the mass is brought near the center of rotation. The coinciding pairs of cylinders of the two sets communicate with each other at their outer ends and the pistons of the coinciding pairs drive crank disks on the shafts of corresponding planet wheels which roll on a wheel keyed on the fixed shaft. The piston rods of the cylinders which form the other limbs of the V's are likewise connected to the crank disks appertaining to the given V. The admission and exhaust valves are operated by means of cams mounted on the fixed shaft at the respective sides of the motor and adapted to operate the valve rods through the medium of levers differing in shape for different cylinders, said cams being arranged to slide on the shaft and thereby to cut out a desired number of cylinders from operation. With this motor are combined fans disposed on each side and mounted on crank disks driven by the piston rods, said fans serving for or maintaining an active current of air for cooling the interior of the motor.

The construction and operation of the motor will be understood from the following description with reference to the accompanying drawing in which:

Figure 1 is a sectional elevation of the motor; Fig. 2 is a cross-section taken between two groups of cylinders on line X—X, Fig. 1; and Fig. 3 is a cross-section through the axis of a cylinder on line Y—Y, Fig. 1; Fig. 4 indicates the different respective posi-

tions of the cams and of the levers that operate the suction valves for the working of a group of two cylinders and for the working of six groups of two cylinders; Fig. 5 represents the different respective positions of the cams and of the levers that operate the exhaust valves for the working of a group of two cylinders and for the working of six groups.

The cylinders, twelve in number for example, are arranged in two sets as follows: Six of them, A¹, A³, A⁶, A⁷, A⁹ and A¹¹, are grouped so as in a manner to form a regular geometrical figure resembling a concave hexagon having three reentering angles. Or this set of six cylinders may be regarded as formed by the combination of three groups of two cylinders set V-wise and put together in such a way that the angles of the V's are reentering angles. The other set of six cylinders, A², A⁴, A⁸, A⁹, A¹⁰ and A¹² is identical with the first and arranged opposite the same. Further, any two cylinders disposed opposite each other, such as A¹, A², for example, communicate with each other at their outer ends as seen in Fig. 3, and the piston rods of the two cylinders that form the limbs of one and the same V, for example, A¹ A¹¹, A² A⁵, A⁷ A⁹, A² A¹², A⁴ A⁶, A⁸ A¹⁰, are connected to one and the same crank disks, e. g. D¹, D³, D⁶, D², D⁴, D⁸. These crank disks are mounted on ball bearings. There are thus side by side two groups of three crank disks, the centers of which form the angles of an equilateral triangle. The opposite or corresponding disks D¹ D², D³ D⁴, D⁵ D⁶ are mounted respectively, each two on a common shaft E¹, E², E³ and on these shafts are keyed planet wheels F¹, F², F³. These planet wheels gear with a fixed wheel G¹ keyed on the fixed shaft H. It will thus be seen that the motion of the piston will be transmitted as follows: The pistons B¹ and B² working in parallel and the pistons B¹¹ and B¹² appertaining to the cylinder A¹¹ A¹² forming part of the same V-groups, will together drive the coupled crank disks D¹ D², that is to say, rotate the planet wheel F¹, while the two other groups of pistons of the V-groups of cylinders will, at the same time, drive the planet wheels F² and F³, and the simultaneous rotation of these wheels in gear with the fixed wheel G¹ will cause the whole arrangement to rotate about the fixed shaft H.

The distribution is effected as follows: Upon the fixed shaft H are slidably mounted two sets of symmetrically disposed cams M and N. One set corresponds to the first group of cylinders and the other to the second group. For the sake of simplicity, I will only refer to one of these two groups in the following description, the operation of the other group taking place in the same way: The admission valves $a^1, a^3, a^5, a^7, a^9, a^{11}$ are those seen in Fig. 1, their rods being marked t . The exhaust valves $a^2, a^4, a^6, a^8, a^{10}, a^{12}$ are arranged similarly but on the other side of the motor; one of them a^2 is seen in Fig. 2. The valve rods t are actuated by bent rocking levers L which are lifted successively by the cams M and N for the admission and by the cams M^1, N^1 for the exhaust. It will thus be seen that for each revolution of the motor about the shaft A there will be two admissions for each cylinder, since the admission valves will be lifted twice. In other words, the cylinders will each give two explosions for a complete rotation for the system, and in order that this may be the case, it is only necessary to make the ratio of the planet wheels F^1 to the fixed wheel G^1 as 1:4. The cylinders may be said to work under identical conditions and grouped as follows: cylinders A^1, A^2 and the cylinders A^7, A^8 , cylinders A^3, A^4 and cylinders A^9, A^{10} , cylinders A^5, A^6 and cylinders A^{11}, A^{12} . The cams M and N will be seen from the center of rotation at an angle of 60° and the levers L will also have the same distance apart. Such is the operation when all the groups of cylinders work simultaneously. I have stated above that when it is desired only to utilize the work of a certain number of cylinders, it is only necessary to alter the position of the cams. For this purpose, the cams can be arranged to slide on the fixed shaft H by means of grooves R in which work the operating fingers Q for imparting the sliding motion. I will take, for example, the admission cams M and N. All these cams M and N have projections disposed in the same manner. The levers L are cut away at the end to different profiles corresponding to the number of valves to be operated. For example, in Fig. 4 the lower diagram shows how the cam M comes successively against the six levers L numbered 1, 2, 3, 4, 5 and 6 in the figure. It will be seen that this contact takes place in an identical way and consequently in this position of the cam, *i. e.*, with M put into the extreme left-hand position, all the cylinders operate. On the other hand, with the cam M moved into the extreme right-hand position as shown in the upper part of the figure, it will be seen that the cam only lifts the lever L numbered 1, *i. e.*, that appertaining to the group of two cylinders A^1 and A^3 . Between these two extreme positions it will

be seen that the cam L will successively lift the levers L numbered 1 and 2, then 1, 2 and 3, and so forth. For the exhaust, the operation is analogous, but in this case the cams M^1 or N^1 all have a collar b. These cams are identical. The lower part of Fig. 5 is a diagram corresponding to the case in which the cam M^1 is slid fully to the left. In this case, the levers Nos. 1, 2, 3, 4, 5 and 6 are actuated in succession and all the cylinders are in operation. In the upper part of Fig. 5, the cam M^1 has been slid to the extreme right and in this case the collar b keeps the levers 2, 3, 4, 5 and 6 raised, that is to say, cuts out the five corresponding groups of cylinders, and only lever No. 1, which is clear of the collar b, operates; this diagram, therefore, corresponds to the cases in which only a group of two cylinders is in operation.

The suction is exerted on the carburetor through an annular chamber 5 in permanent communication therewith. The motor is cooled by a brisk current of air. For this purpose two openings T T^1 are provided on opposite sides of the motor. When the pistons move away from the center in making their return strokes, they draw in fresh air below them through T, this air being heated by and cooling the walls of the cylinders and being expelled through the opening T^1 when the pistons move toward the center on their out strokes. To insure the maintenance of this current of air, it suffices to mount two fans U U^1 on crank disks V V^1 driven by the movement of the piston and to set the blades of these fans so that the current shall flow in the direction mentioned.

What I claim is:

1. A motor of the character described, comprising in combination, a stationary shaft, a plurality of rigidly connected power cylinders revolvable about said shaft, and arranged in two sets in planes normal to said shaft, the corresponding cylinders in each of said sets communicating with each other, pistons in said cylinders, planet wheels engaging said shaft, means connecting each of said planet wheels with said pistons in pairs, inlet ports in the cylinders of one set and outlet ports in the cylinders of the other set, and cam actuated valves for said ports.

2. A motor of the character described, comprising in combination, a stationary shaft, power cylinders rigidly connected with each other and revolvable about said shaft consisting of two sets of six cylinders each arranged in two planes normal to said shaft, the corresponding cylinders in each set communicating with each other, the cylinders in each set being grouped in pairs having their axes forming a recentering angle, pistons in said cylinders, planet wheels engaging said shaft, means connecting each

of said planet wheels with a pair of said pistons, ports in said cylinders and cam operated valves for said ports.

3. In a planetary engine of the character described, a stationary shaft, a planetary wheel revoluble about said shaft, power cylinders having crank connections on both sides of said wheel, a crank casing inclosing said wheel and a fan mounted on each side of 10 the same, one of said fans drawing air into

the casing on one side and the other fan discharging the air from the casing on the opposite side.

In witness whereof I have hereunto signed my name this 15 day of February 1916, in 15 the presence of two subscribing witnesses.

RENÉ BRETON.
